UNITED STATES PATENT OFFICE

164,831

WRIST WATCH CASE OR SIMILAR ARTICLE

Fred Warren, Forest Hills, N. Y., assignor to
Longines-Wittnauer Watch Co., Inc., New York,
N. Y., a corporation of New York

Application February 1, 1950, Serial No. 7,652

Term of patent 14 years

(Cl. D42—8)

To all whom it may concern:

Be it known that I, Fred Warren, a citizen of the United States of America, residing at Forest Hills, Long Island, county of Queens and State of New York, have invented a new, original, and ornamental Design for a Wrist Watch Case or Similar Article, of which the following is a specification, reference being had to the accompanying drawing, forming part thereof.

In the drawings:

Fig. 1 is a front elevational view of a wrist watch case showing my new design, the fine dark lines shown in Figs. 1, 2 and 3 indicate engine turning.

Fig. 2 is a bottom view thereof.

Fig. 3 is a side view thereof; and

Fig. 4 is a rear view thereof.

I claim:

The ornamental design for a wrist watch case or similar article, substantially as shown and described.

FRED WARREN.
